MULTIPLE STEERING HEAD TRICYCLE

Benjamin F. Leber, Chicago, Ill.

Application August 25, 1949, Serial No. 112,260

4 Claims. (Cl. 280—274)

1

This invention relates to tricycles and other cycles.

Children's pedaled tricycles are conventionally made in four frame sizes to cover the age range from about 2 to about 6 years.

It is an object of my invention to provide a tricycle in which the wheel base is variable, enabling the same tricycle structure to accommodate a child throughout an age range heretofore requiring the purchase of a plurality of tricycles of different sizes.

It is also an object to provide a tricycle frame having a plurality of sleeves at different distances forward of the seat post position and adapted selectively to accommodate the tricycle steering post.

A further object is to provide a frame constructed to accommodate a steering post at any of a plurality of distances from the seat post position, without necessitating variation of the position of the frame relative to the ground.

It is another object of my invention to provide a tricycle construction which will enable the purchaser to convert the same interchangeably from a smaller size pedal tricycle to a larger one and vice-versa, without addition or subtraction of any part, thereby obviating the necessity for using different-sized frames and different-sized front wheels and front forks and thus reducing the cost of manufacture and the cost to the purchaser.

Another object is to provide a frame of the character referred to which is of extremely simple and sturdy construction, and which may be manufactured at low cost and will adequately perform any or all of the foregoing functions.

Further objects and advantages of the invention will appear as the description proceeds.

The invention will be better understood upon reference to the following description and accompanying drawings, in which:

Fig. 1 is a side elevational view of a tricycle constructed in accordance with one form of my invention.

Fig. 2 is a fragmentary enlarged side view, partly in section and partly in elevation, of the forward part of the frame and associated structure appearing in Fig. 1.

Fig. 3 is a top plan sectional view taken as indicated by the line 3—3 in Fig. 2.

Fig. 4 is a front elevational view taken as indicated by the line 4—4 in Fig. 2.

Fig. 5 is a top plan view taken as indicated by the line 5—5 in Fig. 1.

Fig. 6 is a sectional view taken as indicated by the line 6—6 in Fig. 1.

Fig. 7 is a sectional view taken as indicated by the line 7—7 in Fig. 2.

Fig. 8 is a sectional view taken as indicated by the line 8—8 in Fig. 2.

Fig. 9 is a fragmentary side elevational view, partly in section, of a modified frame.

2

Referring now more particularly to the drawings, showing exemplary forms of the invention, I have indicated generally at 20 a tricycle comprising a frame 22 which may take various forms and is here shown as comprising a backbone 24 welded as at 26 to a bow 28 whose arms 30 accommodate the rear axle 32 on which the rear wheels 34 are mounted. The backbone 24 has a hole 36 in which the post 38 of a seat 40 is accommodated, the seat being held at any desired up or down adjustment as by a set screw 42.

The forepart 44 of the frame 22 may be of any suitable construction to provide two or more steering post receiving openings in tandem and may be formed for example of a pair of mating sheet metal members 46 and 47 joined together at suitable places as by spot-welding 48 and to provide front and rear bearing sleeves 50 and 52 separated by a gusset 54, and formed with additional upper and lower gussets 56 extending from the rear sleeve to a rearwardly extending socket 60 in which the forward end 62 of the backbone 24 is hydrogen-brazed as at 64 or otherwise integrally secured, and with their front margins 66 united. The sleeves 50 and 52 have upper and lower flanges 68 and 70, providing bearing surfaces.

The fork 72 at the front wheel 73 may be fashioned in any suitable way and is here shown as formed of a single piece of sheet metal, the arms 74 of which are integral with the stem 76. The stem 76 is bent into cylindrical form to have bearing engagement selectively in either of the bearing sleeves 50 and 52, the longitudinal 30 margins of the stem abutting each other and formed with mating dove-tail sockets 78 and projections 80 or otherwise suitably connected so as to be firmly interlocked. When the stem 76 is formed, a collar 82 is slipped over and about 35 the free end of the stem and forced therealong until it is in abutment with the bight 84 of the fork 72 and tightly embraces the stem.

The rear bearing sleeve 52 is provided to accommodate the stem 76 when the tricycle is to be used by a smaller child, and the front bearing sleeve 50 is provided to accommodate the stem when the tricycle is to be used by a relatively larger child. For example, if the smaller child is within the 2 to 3 year range, the larger child 45 would be within the 3 to 4 year range, all within reasonable limits. With a larger front wheel and a larger frame having two bearing sleeves in tandem, the rear bearing sleeve would be used for the child in the 4 to 5 year group, and the front sleeve would be used for the child in the 5 to 6 year group. In assembling the parts, the fork stem 76 is inserted upward into either sleeve 50 or 52 until the collar 82 engages the lower flange 55 60 68 of the sleeve. The stem 76 is of such length that its upper end 66 will project substantially above the upper flange 68 of the sleeve. The

protruding stem end 86 is formed with a hole 88 to allow the point 90 of a set screw 92, threaded in a collar 94 snugly fitted about said stem end, to force the steering post 96, to which the handle bars 98 are connected, into tight engagement with the stem 76 and the stem in turn into tight engagement with the sleeve 52 (or 50, as the case may be). The collars 82 and 94 have bearing engagement with the respective top and bottom flanges 68 and 70 of the selected sleeve.

With the fork 72 assembled with the rear sleeve 52, the wheel base length is as shown in 100 in Fig. 1. With the fork 72 assembled with the front sleeve 50, the wheel base would be substantially longer, as indicated at 102 in Fig. 1. The circle 104 is the locus of the axes of the pedals 106 when the fork 72 is in the position shown in full lines relative to the frame 22. When the stem 76 is assembled in the front sleeve 50, the front wheel 73 is in the position indicated by the circle 108 and the locus of the pedal axes is indicated by the circle 110, providing increased distance of the pedals from the seat 40 to accommodate a larger child.

The front and rear sleeves 50 and 52 may be so arranged that their lower flanges 10 occupy the same position relative to the ground 114, when the frame 22 is used with front and rear wheels of predetermined sizes, so that the position of the frame is the same regardless whether the fork stem 76 is assembled with one sleeve or the other. The sleeves 50 and 52 in such case are parallel, and in any event should be so inclined in service that the proper angle of the steering post 96 is maintained irrespective of the adjustment of the fork 72 in relation to the frame 22.

The sleeve not in use may be suitably covered, as by caps 116 removably held in place as by a bolt 118 and a nut 120.

If desired, the sleeved portion of the frame may be shielded by a suitable shroud (not shown).

In accordance with another form of my invention, shown in Fig. 9, I may provide a frame 118 whose backbone 120 is of such diameter as to surround the intermediate portions of the tandem front and rear sleeves 122 and 124 adapted selectively to receive the fork stem 76 and steering post 96 as in the form of the invention above described. To this end, the backbone 120 is preferably tubular and is formed with front and rear sets of diametrically opposite upper and lower holes 126 and 128 through which the sleeves 122 and 124 project, said sleeves preferably having top and bottom flanges 130 and 134 corresponding to the flanges 68 and 70 above described and hydrogen-brazed as at 132 or otherwise suitably secured to the backbone. The axis of the holes 126 and 128 and hence of the sleeves 122 and 124 are preferably parallel to each other and so arranged that when the frame 118 is assembled with small rear wheels and a substantially larger front wheel, the bottom surfaces 134 of the sleeves are in the same relation to the ground or other support on which the tricycle rests, so that the steering post will extend at the proper steering inclination to the vertical, said inclination being the same regardless whether the front sleeve or the rear sleeve is used. Of course said axes may be at an angle to each other if the sleeve bottoms are arranged in corresponding different relations to a vehicle support when the frame is incorporated in the vehicle. A cap 135 may be driven fitted or otherwise secured so as to close the front end of the backbone 120, and, if desired, the sleeved portions may be shrouded.

Various modifications may suggest themselves

to those skilled in the art without departing from the spirit of my invention, and, hence, I do not wish to be restricted to the specific form shown or uses mentioned, except to the extent indicated in the appended claims, which are to be interpreted as broadly as the state of the art will permit.

I claim:

1. A cycle frame comprising a forepart formed with a pair of front and rear identical cylindrical steering post receiving holes in which a steering post is selectively receivable, whereby, with the same frame, a cycle may be adjusted to accommodate selectively riders of different sizes, said forepart comprising a pair of mating plates, each having a pair of parallel front and rear semi-cylindrical depressions, a depression extending backward from the rear depression, gussets between the last two depressions, and a gusset between said pair of depressions, the respective gussets of said plates being welded together to define said parallel holes and to define a socket extending backward from said rear depression.

2. A cycle frame comprising a forepart formed with a pair of front and rear identical cylindrical steering post receiving holes in which a steering post is selectively receivable, whereby, with the same frame, a cycle may be adjusted to accommodate selectively riders of different sizes, said forepart comprising a pair of mating plates each having a pair of parallel front and rear semi-cylindrical depressions and a depression extending backward from the rear depression, said plates being welded together to define parallel holes and to define a socket extending backward from said rear depressions, and a backbone whose forward end is welded in said socket.

3. A cycle frame comprising a forepart formed with a pair of front and rear identical cylindrical steering post receiving holes in which a steering post is selectively receivable, whereby, with the same frame, a cycle may be adjusted to accommodate selectively riders of different sizes, said forepart comprising a pair of mating plates, each having a pair of parallel front and rear semi-cylindrical depressions and a depression extending backward from the rear depression, said plates being welded together to define parallel holes and to define a socket extending backward from said rear depressions, said plates having parallel semi-annular flanges at both ends of each of said pair of front and rear depressions, said flanges defining annular parallel top and bottom bearing surfaces at the ends of said holes.

4. A cycle frame having a forepart comprising a pair of mating plates welded together and affording front and rear holes adapted selectively to accommodate a steering post and also affording a socket extending rearward from the rear hole to accommodate the forward end of a backbone member.

BENJAMIN F. LEEBEN.
